Attorney

UNITED STATES PATENT OFFICE.

OTTO KAHRS, OF CHRISTIANIA, NORWAY.

SWING-DERRICK FOR SHIPS AND THE LIKE.

1,330,077.

Specification of Letters Patent. Patented Feb. 10, 1920.

Application filed June 25, 1918. Serial No. 241,883.

To all whom it may concern:

Be it known that I, OTTO KAHRS, a subject of the King of Norway, residing at Christiania, in the Kingdom of Norway, 5 have invented certain new and useful Improvements in Swing-Derricks for Ships and the like; and I do hereby declare the following to be a full, clear, and exact description of the invention, such as will enable others skilled in the art to which it 10 appertains to make and use the same, reference being had to the accompanying drawings, and to letters or figures of reference marked thereon, which form a part of this specification.

The present invention relates to swing derricks for ships and the like and has for its object to provide a derrick of this kind which may easily be mechanically driven 15 even when mounted as an ordinary derrick on the mast.

The usual ships derricks are operated by means of ropes or wires fastened to the top of the derrick beam. The operation of the 20 derrick in this manner is slow and clumsy one rope or wire on each side of the derrick beam being necessary each requiring a man for its operation. On the other hand an ordinary derrick crane is too heavy and expensive for installation and use in ordinary 25 ships.

According to the present invention a segment shaped disk is mounted on the ordinary derrick trunnion fastened to the mast, said 30 segment-shaped disk serving as a base plate for the derrick beam and being connected with a mechanical driving apparatus by means of which it may be turned upon its pivot. The derrick beam may suitably consist of truss work or the like in order to obtain sufficient lateral rigidity.

The circumference of the segment may be provided with teeth, so that it may be turned

by means of pinion, screw or the like driven from a suitable source of power.

On the drawing is diagrammatically illustrated a form of the invention.

1 is the mast on which is mounted the ordinary trunnion 2 for a derrick beam.

Trunnion 2 is connected with a segment-shaped disk 3 which serves as a supporting or base plate for the derrick beam 4. The latter may consist of truss work, as illustrated, or may be provided with wire stays or the like in order to obtain sufficient lateral rigidity.

The segment on its circumference is provided with teeth and is engaged by a screw or worm 5, so that it may be turned in both directions by means of handle 6 or any other known hand operated or mechanically driven mechanism.

Claim.

In a swinging loading derrick for ships, the combination of an annular band for attachment to a mast of the ship and carrying a trunnion; a derrick boom; a segment-shaped derrick boom supporting member; means for pivotally connecting the boom to the supporting member; a bearing on said supporting member adapted to engage the trunnion on said annular band, whereby the supporting member may be swung about the axis of said trunnion, said supporting member being cut away to permit this movement without interference with the mast; and means mounted on the deck of the ship for rotating said supporting member.

In testimony that I claim the foregoing as my invention, I have signed my name in presence of two subscribing witnesses.

OTTO KAHRS.
